W. E. ROCKHILL

LIGHTHOUSE

Filed Nov. 23, 1927.

UNITED STATES PATENT OFFICE.

WILLIAM E. ROCKHILL, OF SPOKANE, WASHINGTON.

DESIGN FOR A LIGHTHOUSE.

Application filed November 23, 1927. Serial No. 24,261. Term of patent 14 years.

To all whom it may concern:

Be it known that I, WILLIAM E. ROCKHILL, a citizen of the United States, residing at Spokane, in the county of Spokane and State of Washington, have invented a new, original, and ornamental Design for a Lighthouse, of which the following is a specification, reference being had to the accompanying drawing, forming a part thereof.

In the drawing:

Fig. 1, is a front elevation of a light house showing my new design.

Fig. 2 is a plan view thereof on a reduced scale.

I claim:

The ornamental design for a light house, substantially as shown.

WILLIAM E. ROCKHILL.
